UNITED STATES PATENT OFFICE

FRANZ PUENING, OF ASPINWALL, PENNSYLVANIA

APPARATUS FOR CARBONIZING COAL

Application filed August 13, 1925. Serial No. 50,011.

My invention relates to apparatus for carbonizing or otherwise heat-treating coal, lignite, or other carbonaceous material, and for convenience of description it will be recited 5 as applied particularly to the carbonization of coal.

My invention has for its object the provision of an improved apparatus possessing the following advantages, taken either singly or 10 in various combinations: The uniform heating of a stationary body of coal or other carbonaceous material; a continuous coking process wherein the coal is undisturbed during heat treatment; providing a continuous 15 supply of coal past a plurality of coking receptacles, in volume exceeding that required to fill the receptacles, so that the coal which is conducted first past filled receptacles or trays to those which are more remote will 20 not be permanently heated; simultaneously charging the trays or other receptacles; continuously removing the coke from the trays, and to simplify and improve generally the 25 structure, operation and processes of heat-treating materials.

The invention of the present application is similar in certain of its aspects to that of my Patent No. 1,698,349, granted January 8, 1929. Such similarities include the provision 30 of a plurality of continuous annular spaces or carbonizing chambers that alternate with heating chambers to form a structural unit and of a second structural unit for supplying coal to the carbonizing chambers, the structural units being relatively rotatable. In each arrangement, coal is continuously supplied to the carbonizing chambers and the carbonized material is continuously removed therefrom.

Some of the forms of apparatus by means of which my invention may be practiced are shown in the accompanying drawings, wherein Fig. 1 is a vertical sectional view of a portion of the apparatus, taken on the line 1-1 of Fig. 2; Fig. 2 is a horizontal sectional view taken on the line 2-2 of Fig. 1; Fig. 3 is a view taken on the line 3-3 of Fig. 1; Fig. 4 is a fragmentary view taken on the line 4-4 of Fig. 3; Fig. 5 is a sectional view 45 of the piston for reciprocating heating gases,

taken on the line 5-5 of Fig. 1; Fig. 6 is a view, on an enlarged scale, of a portion of the apparatus of Fig. 3; Fig. 7 is a view similar to Fig. 3, but showing a modified form of apparatus; Fig. 8 is a view taken on the line 8-8 of Fig. 7; Fig. 9 is a plan view showing the manner in which the rotatable carrier of Fig. 7 is driven, and Fig. 10 is a view showing a tray of different form than those of Figs. 1 and 7. 55

As stated above, my invention is shown as employed in connection with the coking or carbonization of coal. The apparatus comprises a brickwork 10, preferably of circular cross section, which is provided with chambers and passages for heating gases, as hereinafter set forth, and is supported by a series of steel posts 11. The brickwork 10 is provided with a central passage 12, through which heating gases may enter and also with a pair of chambers 13 and 14 that communicate through conduits 15 and 16, respectively (Fig. 2) with a chamber 17 in which an oscillatory piston 18 is mounted for oscillation in a manner to be hereinafter described. 60

A cylindrical casting 20 is mounted upon the brickwork 10 and is provided with a series of inclined shelves or trays 21 upon which the coal to be treated is placed.

A cylindrical casing or housing 22 surrounds the member 20, having spaced relation therewith. The housing 22 is provided at its lower edge with a flange 23 that extends into an annular groove 24 which contains water or sand, so that a water or sand seal is provided against the escape of coal gases. At its top the housing 22 is provided with a down-turned flange 25 which extends into an annularly recessed member 26 that contains water or sand to seal the top of the housing 22 against the escape of gases from the coal heated within the housing. An annular trough 27 is fixedly mounted beneath the rotatable housing 22. 80

A coal hopper 28 is provided, having a chute 29 extending into and secured to the housing 22, as shown in Fig. 4, so that the coal can flow from the chute to the trays.

The housing 22 is secured to an annular framework 30 that is provided with a circular 85

100

rack bar 31 which is driven by a toothed gear wheel 31^a that is secured to a shaft 33. A portion of the underside of the bar 31 is left smooth, so that it may be supported by un-
5 toothed idler rollers 32 carried by shafts 33 and 33^a. The shafts 33 and 33^a are mounted in bearings that are supported upon I-beams 34 which are mounted on a framework 35, so that the coal hopper 28 is ultimately sup-
10 ported by the frame 35.

The trays 21, as well as the parts enclosed thereby, are stationary, while the housing, together with the coal hopper, are rotated by means of a pulley 36 secured to the shaft 33
15 and rotated from any suitable source of power. The axes of the shafts 33 and 33^a are stationary so that as the pulley 36 is rotated the gear wheel 31^a will, by reason of its engagement with the rack
20 31, cause rotation of the housing 22. As the housing 22 rotates the coal will flow from the chute 29 to the various trays 21, in the manner shown in Fig. 4. The coal is preferably fed through the chute 29 in quantity
25 greater than that required to fill the shelves and the surplus coal will pass out of the end of the chute 29 to the trough 27, from whence it is scraped into a chute 37, by a scraper 41 that is carried by the housing 22, at some
30 distance to the rear of the chute 29. A discharging mechanism 37^a is attached to the bottom of chute 37 from which the coal may be returned in any suitable manner as by a conveyor, (not shown) to the hopper 28.
35 The discharging mechanism 37^a so retards the flow of coal through chute 37 as to form a seal which prevents escape of coal gases. This arrangement insures not only an ample supply of coal to fill the trays but the supply is
40 in such volume that coal passing the upper trays is not excessively heated or partially coked before reaching the lower trays, as perhaps would be the case if coal were fed through the chute 29 in quantity only sufficient to fill the trays. The chute 29 terminates some distance above the coal collecting trough 27 so that the coal will flow freely.
45 Spring-pressed plungers 38 (Figs. 4 and 6) are provided for yieldingly holding the chute 29 against the trays 21, and braces 39 are provided for rigidly holding the chute 29 in proper vertical alignment, against the drag resulting from movement of the housing 22 around the trays, the braces being welded or
50 otherwise secured to the housing 22 and the chute. The chute 29 is widened within the housing 22, and partitioned so as to form supplementary chutes 40 (Fig. 4) so that spilled or surplus coal which overflows the edges of the trays will be directed to the trough 27.
55

A series of scrapers 46—one for each tray—are secured to the housing 22 in such position that their forward pointed ends extend into
60 the spaces between adjacent trays, in the

manner shown in Figs. 3 and 4. The housing 22 rotates in the direction indicated by the arrows in Fig. 4, and the scrapers 46 are in advance of the coal delivery chute 29, so that the trays will be cleared of the coal that was
70 deposited during the previous revolution of the housing 22 and which has meantime been carbonized or coked. The trays are heated, in a manner to be hereinafter described, and the housing 22 is rotated at such rate of speed
75 relative to the temperature of the trays and the volume of coal deposited thereon that the heat treatment of the coal deposited on the trays will be completed during the period required for a single revolution of the housing.
80 This arrangement permits of continuous operation of the apparatus, and insures uniformity of product.

A flanged cover 48 (Fig. 6) is secured to the housing 22 at a point beneath the scrapers 46, by means of a casting 48^a, so that the coke which is removed from the trays 21 will fall upon the coal trough cover 48 and slide into a stationary trough 49 from which it is removed by ploughs 50 that are also secured to the housing 22. The trough 49 is provided with annular flanges 51 between which an annular flange 52 carried by the housing 22 is disposed, so that a water or sand seal may be provided against the escape
95 of coal gases. The coal gases formed during the process may be conducted away from the apparatus through an outlet pipe 53 (Fig. 3).

In order to prevent the newly formed coal gas from entering the surplus coal trough 27,
100 I supply a quantity of dry gas to the coal trough 27, through the pipe 54. In this manner I create a slight pressure within the trough 27, so that the newly formed coal gases carrying tar vapors cannot enter the trough where their vapors would be condensed and cause the surplus coal to become
105 a pasty mass.

The trays may be uniformly heated by means of heating gases circulated somewhat after the manner shown in my prior patents, No. 1,542,954 and No. 1,542,955, issued June 23, 1925, but I will briefly describe the manner in which heating gases are circulated through the present system in order to effect uniform heating of the trays, and therefore uniformity of product. The heating gases, for carbonizing the coal, are conducted to the chambers and passages within the tray-supporting cylinder 20, through the inlet 12.
110

The piston 18 is secured to a shaft 60 that may be oscillated by a crank arm 61 which is connected to a reciprocating rod 62. The rod 62 may be moved back and forth in any desired manner, as for instance that shown in my Patent 1,542,955. Exhaust pipes 63 and 64 are connected to the outer ends of conduits 15 and 16, respectively, and mechanism such as that shown in my said patent may be provided for closing the valves 65 in exhaust
115

pipe 63 when the piston is moving in a clockwise direction as indicated by the arrows in Fig. 1. This prevents heating gases being driven from the conduit 15 through the exhaust. Simultaneously valve 66 in exhaust pipe 64 is opened so that waste heating gases may be exhausted from the conduit 16. When the piston 18 is moved in the opposite direction, the positions of the valves 65 and 66 will 10 be reversed since the piston will then force heating gases through the conduit 16 and the exhaust from the conduit 15 must be opened so that some of the cooled gases can be conducted away, to permit entry of additional hot gases through the conduit 12.

When the piston 18 is moving in a clockwise direction, as above explained, a flow of gas is set up through conduit 15, chamber 13, passages 67, 68, 69, 70, 71, 72 and 73 to the 20 chamber 14 and conduit 16, since the conduit communicates with that portion of the chamber 17 to the right hand side of the piston 18. A combined pressure and vacuum effect is thus secured by the piston, in the conduits 15 and 16, respectively, to effect movement of the gases as above referred to. At this time a small amount of gas will exhaust through the pipe 64 to permit entry of heated gases through the conduit 12, as above explained. 30 When the gas is flowing in the direction indicated by the arrows, as above described, heated gases in volume substantially equal to that exhausted through pipe 64 will enter the chamber 14 through perforations 77 that are 35 located in one wall of the conduit 12.

Upon its return stroke, in a counter clockwise direction, the piston will force gases through the conduit 16, in directions reverse to those above described, surplus gas being 40 then exhausted through pipe 63 and being replaced by heated gases which enter the system through the conduit 12 and openings 78.

The gas in passing through the passage 70 heats the cylinder 20 and trays 21 and thereby 45 effects carbonization of the coal, as above explained.

In Figs. 7, 8 and 9 I have shown apparatus which is similar in many respects to that of Figs. 1 to 6. This apparatus comprises a 50 cylindrical casting 80 supported upon brick-work 81 that is provided with a conduit 12^a through which heating gases may enter, and with conduits 15^a and 16^a, corresponding to the conduits 12, 15 and 16 of Fig. 2. The 55 gases may be reciprocated through the system by means of the apparatus shown in one of my patents above referred to, or in any other suitable manner, and flow from conduit 15^a through passages 82 and circumferential 60 channels or heating chambers 83, in both directions, meeting at the point 84 from where they flow through openings 84 and 85 to conduit 16^a. Fresh heating gases enter the system from the conduit 12^a, through passages 65 102 alternately in opposite directions, de-

pending upon the direction of flow through the conduits 15^a and 16^a.

In this form of device, as in the form shown in Fig. 1, the trays 86, which constitute the floors of annular coking chambers, are 70 stationary and a housing 87 is provided with an annular rack 88 that engages with gear wheel 89, driven from any suitable source of power, and the housing thereby rotated. Only one gear wheel 89 is required, a series of 75 idling rollers 90 being provided for supporting the housing 87. A shaft 91 is mounted in bearings secured to the housing 87 and has a gear wheel 92 which meshes with a gear wheel 93. The gear wheel 93 in turn meshes with a gear ring 94 that is fixedly mounted upon a frame 95 which is in turn supported upon the brickwork 81. Other gear wheels, of various ratios, may be substituted for the gear wheels 92 and 93 or such gear wheels 85 interchanged in order to vary the rate of speed of rotation relative to the rotary movement of the housing 87. It will be seen that as the housing 87 is rotated the gear wheels 93 and 92 will be also rotated by reason of 90 their connection with the gear ring 94.

Charging discs 96 are secured to the shaft 91 and project into the spaces above the trays 86. A coal hopper 28^a and chutes 29^a are carried by the housing 87 so as to cause coal to be deposited upon the discs 96. Rotation of these discs will carry the coal to the spaces above the trays and the coal will then be scraped from the discs on to the trays by scrapers 97 that are pivotally connected to the housing 87 as shown in Fig. 8. Scrapers 46^a are secured to the housing 87 at a point in advance of the discs 96 so as to remove the coke from the trays as the housing is rotated. The coal gases are conducted from the housing 87 through a draw-off pipe 53^a. The housing 87 is provided with flanged extensions 98 and 99 that cooperate with annular channels containing water or sand to provide 100 a seal against escape of coal gases. 105

Leveling bars 103 (Fig. 8) are provided for spreading the coal upon the trays, such bars being secured to the housing 87 to the rear of the scrapers 97. 110

The coke is discharged from the trays through a hopper 100 by the coke discharging mechanism 101 that is provided for the purpose of preventing escape of coal gases to the atmosphere. 115

If desired, coal trays for the coal and coke and ploughs or scrapers for removing the coal and coke therefrom may be provided in the structures of Figs. 7 to 9, as in the case of the structure of Figs. 1 to 6. Furthermore, inspection doors or openings may be provided in the walls of the apparatus so that the interior thereof may be inspected from time to time. 120

In some cases I may desire to preheat the coal which is supplied through the chute 29. 130

In Fig. 10 trays 86^a are shown, having the same general form as the trays 86 of Fig. 7, but having ribs upon their upper surfaces.

These ribs provide greater contacting surface for the coal so that heat is more readily transferred thereto. Also, the coke made on a tray of the above description will have the form of the grooves instead of being a thin flat piece. The coke in the depressions will be of thicker cross section and therefore not so easily broken into pieces so small as to have considerably less market value than the larger pieces.

It is contemplated that the position of the trays and the coal chutes may be reversed. That is the trays may be disposed circumferentially of the coal chute instead of the coal chutes being disposed at the periphery of the trays.

I claim as my invention:

1. A carbonizing retort comprising in combination a set of alternately superposed annular carbonizing recesses and heating walls, the former being closed at one circumference of their annular contour and being wholly independent of each other and separated by the heating walls, said set of alternately superposed annular recesses and heating walls forming a structural unit, and a casing surrounding said superposed recesses and heating walls and forming a second structural unit, one of the structural units being rotatable relatively to the other.

2. A carbonizing retort comprising in combination a set of alternately superposed annular carbonizing recesses and annular heating recesses, one of these two sets of annular recesses being closed at their inner circumference and being wholly independent of each other, and the other annular recesses being closed at their outer circumference and open at their inner, said set of alternately superposed annular carbonizing recesses and heating recesses forming a structural unit, a casing surrounding said superposed carbonizing recesses and heating recesses and forming a second structural unit, one of the structural units being rotatable relatively to the other.

3. A carbonizing retort comprising in combination a set of alternately superposed annular carbonizing recesses and heating walls, the former being closed at their inner circumference and being wholly independent of each other and separated by the heating walls, said set of alternately superposed annular recesses and heating walls forming a structural unit, and a casing surrounding said superposed recesses and heating walls and forming a second structural unit, one of the structural units being rotatable relatively to the other.

4. In apparatus for carbonizing coal, a plurality of superposed trays, heating walls for heating said trays, means for continuously

moving a stream of coal past said trays, and means for withdrawing a portion only thereof to fill the trays.

5. In apparatus for carbonizing coal, a plurality of stationary superposed annular trays, heating walls for uniformly heating each of said trays and for separating said trays, means for continuously supplying untreated coal to each of said trays, and means for continuously removing carbonized coal from all of said trays simultaneously.

6. In apparatus for carbonizing coal, a plurality of stationary superposed annular trays, heating walls for uniformly heating each of said trays, and means for continuously supplying untreated coal to each of said trays simultaneously from a moving body of coal.

7. In apparatus for carbonizing coal, a plurality of superposed trays, annular heating walls for heating said trays, means for continuously charging each of said trays with untreated coal, and means for continuously removing treated coal from each of said trays at the rate at which they are charged.

8. In apparatus for carbonizing coal, a plurality of superposed annular trays, heating walls for separating and for heating said trays, a scraper rotatable about the axis of each of said trays for removing the treated coal therefrom, a movable chute for supplying untreated coal to all of said trays, and means for rotating the scrapers and the chute at such speed that coal is deposited to the rear of the scrapers and is treated during substantially one revolution of said scrapers.

9. In apparatus for carbonizing coal, a cylindrical frame whose axis is vertical and which is provided with a plurality of annular trays upon one of its curved peripheries, heating walls between said trays, said trays each being inclined from its outer edge downwardly to the wall of the cylinder, and means for simultaneously supplying material to be carbonized to each of said trays, and means movable with the supplying means for removing carbonized material from said trays.

10. In apparatus for carbonizing coal, a vertical cylindrical frame and provided with a plurality of alternate superposed annular trays and heating walls upon one of its curved peripheries, a chute for supplying each of said trays with material to be carbonized, and means for removing carbonized material from said trays.

11. In apparatus for carbonizing coal, a stationary vertical frame that is circular in cross-section and provided with a plurality of superposed annular trays upon one of its curved peripheries, heating walls for each of said trays, said trays each being inclined from its outer edge downwardly to the wall of the cylinder, and adapted to receive material for heat treatment, and means for sup-

plying untreated material to and removing treated material from each of said trays simultaneously.

12. In apparatus for carbonizing coal, a vertical cylindrical frame provided with a plurality of separate superposed annular trays upon one of its curved peripheries, said trays each being inclined from its outer edge downwardly to the wall of the cylinder and adapted to receive material for heat treatment, and heating walls between said trays.

13. In apparatus for carbonizing coal, a vertical cylindrical frame provided with a plurality of separate superposed annular coking recesses upon one of its walls and opening outwardly therefrom, heating walls for said coking recesses, and all of said coking recesses being adapted to receive material simultaneously for heat treatment, and means for continuously removing treated material from said coking recesses.

14. In apparatus for carbonizing coal, a series of superposed annular trays having their inner edges secured to a cylindrical framework, a wall partially enclosing said trays and framework but spaced from the outer edges of said trays, and means for supplying a stream of coal between said wall and said trays.

15. In apparatus for carbonizing coal, a series of superposed annular trays having their inner edges secured to a cylindrical framework, a wall partially enclosing said trays and framework but spaced from the outer edges of said trays, and means for supplying a stream of coal between said wall and said trays, the said wall and the coal supplying means being movable relatively to the trays, circumferentially thereof.

16. In apparatus for carbonizing coal, a series of superposed annular trays each having one of its edges secured to a cylindrical framework, a wall partially enclosing said trays and framework but spaced from the free edges of said trays, and means for supplying a stream of coal between said wall and said trays, the said wall and the coal supplying means being movable relatively to the trays, circumferentially thereof.

In testimony whereof I, the said FRANZ PUENING, have hereunto set my hand.

FRANZ PUENING.
